UNITED STATES PATENT OFFICE.

ELROY A. CHASE, OF NORTHFIELD, VERMONT.

GRANITE-WORKING MACHINE.

Application filed February 11, 1921. Serial No. 444,221.

To all whom it may concern:

Be it known that I, ELROY A. CHASE, a citizen of the United States, residing at Northfield, in the county of Washington 5 and State of Vermont, have invented a new and useful Granite-Working Machine, of which the following is a specification.

This invention relates to a granite working machine, and particularly to an improved tool for use therein. It is the general object of my invention to provide a machine by which blocks of granite or similar stone may be quickly and economically provided with flat finished surfaces.

For this purpose I preferably support the block of granite in a chuck by which the stone is rotated during the finishing operation.

An important feature of my invention relates to the provision of a novel and very effective tool for removing the surplus or waste stone from the face of the block. It is well understood in the art that granite cannot be successfully subjected to the action of cutting tools, like marble or other soft stone, but that it must be worked with a crushing or breaking process in which there is no substantial sliding movement between the work and the tool.

Accordingly, this feature of my invention relates particularly to the provision of an improved and novel granite working tool so constructed that it will act by crushing or breaking rather than by cutting the stone.

In the preferred form I provide a tool comprising a plurality of discs having beveled edges, and collectively mounted for free and independent rotation upon a movable 40 tool carrier. The discs are progressively increased in size rearwardly from the stone and the spaces between the discs are likewise progressively increased, providing greater clearance for the larger pieces of stone 45 which are removed by the rear or outer discs.

A further feature of my invention relates to the provision of improved bearings for the discs, to resist the heavy strain to which the discs are subjected when in operation and to permit them to rotate freely and independently under all conditions.

My invention further relates to a construction whereby worn parts may be

cheaply and readily replaced and to certain arrangements and combinations of parts which will be hereinafter described, and more particularly pointed out in the appended claims.

A preferred form of my invention is shown in the drawings, in which—

Fig. 1 is a side elevation, partly in section, of my improved granite working tool;

Fig. 2 is a similar view of a modified construction, and

Fig. 3 is a plan view of a machine for which the tools of Figs. 1 or 2 are particularly adapted.

Referring first to Fig. 3, I will describe the general features of the granite working machine therein shown. I have shown a block of granite firmly secured in a chuck 10 mounted on the end of a shaft 11, rotatable in bearings 12 on a frame or base 13. The shaft 11 may be rotated in any convenient manner, as by a belt 14 running over a pulley 15 on the shaft 11. A tool carriage 16 is mounted to slide on a table 18 and may be adjusted thereon by a screw 19 and hand wheel 20. The table 18 is movable on guides 21 in any convenient manner, as by a screw 22 which may be rotated manually or automatically in any suitable manner. A second carriage 23 may be mounted on the table 18 on which it is adjustable by a screw 24 and hand wheel 25. The carriage 23 supports a motor 26 belted to a shaft 27 upon which a plurality of grinding or finishing wheels 28 are secured.

The tool carriage 16 is provided with a bearing 30 in which a shaft 31 (Fig. 1) is slidably but non-rotatably mounted. A plurality of work engaging discs 32, 33, 34 and 35 are mounted to rotate freely and independently on the shaft 31, or preferably upon a bushing 36 fitting the end of the shaft 31. A head 37 is secured to the end of the shaft 31 and is preferably provided with an oil-hole 38 by which oil is supplied for lubricating the disc bearings.

Thrust bearings are provided between each pair of adjacent discs, these bearings being preferably of the ball bearing type. The discs 32 and 33 are located somewhat closely together and the discs 33 and 34 are spaced a little further apart by using larger balls in the bearing 40. Wider separation between the discs 34 and 35 is secured by

the use of a spacing disc 41 in addition to the ball bearing 42. A ball bearing 43 is also provided for the disc 35, the thrust being taken by a steel ring 44 set into the face 3 of a flange 45 keyed to the shaft 41 but slideable thereon. Adjusting and lock nuts 46 and 47 are threaded on the shaft 31 and may be used to adjust the shaft longitudinally, to provide exactly the right clearance between 10 the discs so that they may rotate freely but without lost motion.

The discs 33, 34 and 35 are provided with beveled edges and the small disc 32 is preferably provided with a double beveled edge, 15 as shown in the drawings. This permits the working diameter of this disc to be somewhat larger than would be the case if the single beveled edge were employed.

The action of the cutting tools is clearly 20 shown in Figs. 1 and 2, in which it appears that the outer or larger disc 35 first engages the stock as shown, removing the surplus stock therefrom in relatively large pieces.

The other discs 34, 33 and 32 thereafter successively engage the stone and remove layers 25 of decreasing thickness from the face thereof, the disc 32 removing a thin layer only, and leaving a relatively smooth surface for the operation of the grinding wheels 28.

My improved tool in one passage over the surface of the block can thus remove four successive layers of material.

In Fig. 2 I have shown a modified construction in which the smallest disc 50 is secured to the end of the shaft 51, which extends through a sleeve 52 rotatably mounted in thrust roller bearings 53 and 54. The remaining discs rotate freely upon a bushing 55 as in the form previously described. The operation of the tool is identical.

By the construction shown in either Fig. 1 or 2, the cost of replacement is reduced to a minimum, as the bushings 36 or 55 may be short sections of ordinary pipe or tubing, upon which the hardened steel discs rotate practically without wear, while the bushing may be very easily and cheaply replaced as often as may be necessary.

The provision of ball or roller bearings between the discs is of great importance, as it permits the discs to rotate freely under all circumstances, no matter how great pressure they may sustain. As the edge of the 55 discs would be quickly destroyed by any relative sliding movement between the discs and the stone, this provision for free rotation under all conditions is of greatest importance.

The application of my improved granite working tool to a machine of the type shown in Fig. 3, enables me to secure a finished and polished surface on a large block of granite at a single operation, and at a 65 very great reduction in time and labor.

The construction shown in Fig. 2 is not claimed specifically herein but forms the subject matter of a divisional application Serial No. 642,362, filed by me May 29, 1923 and patented July 29, 1924, No. 1,503,026. 70

Having thus described my invention, it will be evident that other changes and modifications can be made therein by those skilled in the art within the spirit and scope of my invention as set forth in the 75 claims, and I do not wish to be otherwise limited to the details herein shown, but what I claim is:

1. A granite working tool comprising a shaft, a plurality of work-engaging discs 80 centered on said shaft and slideable axially thereon toward and from each other and each freely and independently rotatable in substantially radial planes about the axis of said shaft, and thrust bearings between said 85 discs to limit relative axial movement thereof.

2. A granite working tool comprising a shaft, a plurality of discs centered on said shaft and each freely and independently rotatable in substantially radial planes about the axis of said shaft, and anti-friction devices 90 engaging said discs at points removed from said shaft.

3. A granite working tool comprising a 95 shaft, a plurality of discs centered on said shaft and each freely and independently rotatable about the axis of said shaft, and anti-friction devices engaging said discs at points removed from said shaft, said discs 100 having beveled working edges.

4. A granite working tool comprising a shaft, a plurality of discs of unequal size each freely and independently rotatable about the axis of said shaft, and anti-friction devices engaging said discs at points remote from said shaft, said discs having beveled working edges and the smallest disc 105 having a double beveled edge.

5. A granite working tool comprising a 110 shaft, and a plurality of discs each freely and independently rotatable about the axis of said shaft, said discs being of unequal diameters and being axially separated from each other by spaces which increase progressively with the increased diameter of the discs which are separated.

6. A granite working tool comprising a shaft, and a plurality of discs each freely and independently rotatable in substantially radial planes about the axis of said shaft, said discs being of unequal size and being unequally spaced from each other along the shaft with the larger discs more 120 widely separated, and the working edges of said discs defining a substantially conical structure.

7. A granite working tool comprising a shaft, a removable bushing on said shaft, a plurality of beveled discs freely and inde- 125

pendently rotatable on said bushing, and anti-friction spacing devices between adjacent discs.

8. A granite working tool comprising a shaft having a fixed head, a support in which said shaft is non-rotatably mounted, a flange slideable but non-rotatable on said shaft, a plurality of work engaging discs rotatable on said shaft, anti-friction devices separating said discs from each other and from said flange, and means to adjust said shaft axially in its support.

9. A granite working tool comprising a shaft having a head, a bushing removably mounted on said shaft, a plurality of work

engaging discs freely and independently rotatable on said bushing, and spacing devices between said discs, said discs increasing in diameter and in spacing rearward from the shaft head.

20

10. A granite working tool comprising a shaft, and a plurality of substantially flat circular stone-crushing discs centered on said shaft and freely and independently rotatable about the axis of said shaft, said discs increasing in relative diameter rearward from the outer end of said shaft.

25

In testimony whereof I have hereunto affixed my signature.

ELROY A. CHASE.
